UNITED STATES PATENT OFFICE.

EDWARD L. HOLMES, OF NEW YORK, N. Y., ASSIGNOR TO HOLMES NAVIGATING APPARATUS CO., INC., OF NEW YORK, N. Y., A CORPORATION OF NEW YORK.

ALTERNATING-CURRENT RELAY.

Application filed January 24, 1925. Serial No. 4,618.

The following is a description of an alternating current relay embodying my invention in the form and manner at present preferred by me; but it will be understood that various modifications and changes may be made without departing from the spirit of my invention and without exceeding the scope of my claims.

My invention will best be understood by reference to the accompanying drawings, in which Fig. 1 is a front elevation of my relay; and Fig. 2 is a plan view thereof. Like reference characters indicate like parts throughout the drawings.

Referring to the drawings, 1 represents a base upon which are mounted two brackets 2 and 2^a and two standards 3 and 3^a. Supported on bracket 2 are coils 4 and 4^a, and on bracket 2^a, coils 5 and 5^a. Coil 4 has core 6, coil 4^a has core 6^a, coil 5 has core 7, and coil 5^a has core 7^a. Cores 6 and 6^a are supported by yokepiece 8, and cores 7 and 7^a are supported by yoke piece 8^a. Attached to yoke piece 8 is threaded rod 9, supported in standard 3; and attached to yoke piece 8^a is threaded rod 9^a, supported in standard 3^a. Knurled nut 10 and spring 11 control the position of coils 4 and 4^a; and knurled nut 10^a and spring 11^a control the position of coils 5 and 5^a—whereby the air-gaps between the cores and the armature may be adjusted. Pivotaly supported in bracket 12 on said base 1 is armature 13, carrying springs 14 and 14^a. Spring 14 carries contact 15, co-acting with secondary-circuit contact 16 on adjusting screw 17, which may be held in position by knurled nut 18. Spring 14^a carries contact member 15^a, coacting with secondary-circuit contact member 16^a on adjusting screw 17^a, which may be held in position by knurled nut 18^a.

I have found that by placing coils 4 and 4^a in series in one circuit connected to a source of alternating current, and coils 5 and 5^a in series in another such circuit in shunt to said first-named coils, and by so connecting these pairs of coils in said circuits that at any instant the polarity of coil 4 is the same as that of coil 5, and the polarity of coil 4^a is the same as that of coil 5^a, the magnetic field of each pair of coils is practically confined to such pair, its yokepiece and to armature 13. I preferably maintain both pairs of coils continually energized, the armature normally remaining in

a neutral position wherein it closes neither of the secondary circuits which include contacts 16 and 16^a, respectively. The armature is attracted by one or other of the pairs of coils in response to a differential between the resistances of the two circuits including said pairs of coils, respectively; and by reason of connecting the pairs of coils in the manner described, upon the occurrence of such a differential, a pull of maximum efficiency is exerted upon the armature.

In all alternating current relays with which I am familiar, the armature continually vibrates at a frequency corresponding with the frequency of alternations of the current. I have found that regardless of how alternating current relays may be adjusted and irrespective of what type of armature springs may be employed, and of the tension of such springs, it is not possible, under the condition of variations in current flowing through the coils, to maintain a continuous contact between the armature contact members and their coacting contact members. I overcome this objectionable feature by opposing gravitational force to the magnetic attraction of the coils so that when the energization of one pair of coils exceeds that of the other pair even by a very considerable extent, the vibratory action is confined to the armature 13 and is not communicated through springs 14 and 14^a to the armature contact member which is closing a secondary circuit. As a result, I am able to maintain the continuity of contact in such secondary circuit. I accomplish this result by attaching to one side of the upper end of armature 13 thread 19, carrying weight 20—the opposite end of said thread being connected to spindle 21, mounted in an arm of standard 3, the tension of such thread being adjustable by means of manual rotation of knurled handle 22. A similar thread 19^a, carrying weight 20^a, has one end attached to a corresponding spindle 21^a mounted in bracket 3^a, and adjustable by manipulation of handle 22^a. The effect of these suspended weights appears to be to sufficiently damp or limit the amplitude of the vibrations of armature 13 to restrict the same within the range of resilience of contact springs 14 and 14^a, and thereby prevent interruption of the continuity of contact in the secondary circuit. While I have illustrated opposing coils, it will, of course, be understood that

105
110

my invention is applicable to a single coil or coils which actuate the armature in one direction, one of these suspended weights being utilized for resisting the movement of the armature.

What I claim as new and desire to secure by Letters Patent of the United States is:

1. In an alternating current relay, a coil, an armature actuated by said coil, a contact member yieldingly mounted on said armature, a stationary contact member coacting with said first-named contact member and a weighted connection between said armature and an outside support for damping the vibrations of said armature and preventing the separation of the contacts when in engagement.

2. In an alternating current relay, opposing coils, an armature actuated by said coils, contact members yieldingly mounted on said armature, coacting stationary contact members and a plurality of weights suspended between said armature and outside supports for damping the vibrations of said armature in order to prevent separation of the contacts when in engagement.

3. In an alternating-current relay, opposing coils for actuating an armature to control secondary circuits and means comprising weights acting upon the armature for limiting the amplitude of its vibrations in order to permit maintenance of a continuous electrical contact in one of said secondary circuits.

4. In an alternating current relay, opposing coils, an armature actuated by said coils, contact members yieldingly mounted on said armature, coacting stationary contact members and a plurality of weights suspended between said armature and outside supports for damping the vibrations of said armature in order to prevent separation of the contacts when in engagement and means for adjusting the position of said weights.

5. In an alternating current relay, a plurality of stationary contacts, coacting contacts associated with an armature, and a plurality of magnet coils constructed and arranged to be continuously energized and to move said armature in response to a differential in such energization and means for damping the vibrations of said armature.

6. In an alternating current relay, a plurality of stationary contacts, coacting con-

tacts yieldingly mounted upon a pivotally supported rigid armature, a plurality of magnet coils constructed and arranged to be continuously energized and to move said armature upon the occurrence of a differential in such energization and means for damping the vibrations of said armature.

7. In an alternating current relay, two magnet coils, electrically connected to be of like polarity when energized and to oppositely attract an armature controlling secondary circuits, and means for normally maintaining said armature in a neutral position and preventing opening of said secondary circuits in response to alternations of the current flowing through said coils.

8. In an alternating-current relay opposing magnet coils electrically connected to be of like polarity when energized, an armature responsive in movement to a differential in the current flowing through said coils, electrical contacts carried by said armature, coacting stationary electrical contacts, secondary circuits including said armature contacts and stationary contacts, and means associated with said armature for damping its movements to prevent opening of said secondary circuits in response to alternations in current flowing through said coils.

9. In an alternating current relay a magnet coil, a second magnet coil electrically connected to be when energized of like polarity with and to magnetically oppose said first magnet coil, an armature constructed and arranged to close one or other of two secondary circuits in response to a differential in the current flowing through said magnet coils, and suspended weights acting upon said armature to normally maintain it in a neutral position and to damp its movements in order to prevent opening of either of said secondary circuits by the alternations of current flowing through said coils.

10. In an alternating current relay, an armature, contacts mounted thereon, coacting stationary contacts, opposing and continuously-energized coils constructed and arranged to move said armature in response to a differential in said energization and means for maintaining said armature in a neutral position with reference to said contacts until the occurrence of such differential in energization.

EDWARD L. HOLMES.
